TENSION DEVICE FOR TEXTILE MACHINES

St. Clair Lake, Poughkeepsie, N. Y.

Application January 26, 1934, Serial No. 708,379

4 Claims. (Cl. 8—19)

This invention relates to a tension device for textile machines, and more particularly to that class known as bleaching, dipping and dyeing tanks where textile fabric is carried from a supply roll through the liquid in the tank and is then either rolled upon a take off roll, or the movement is reversed and the fabric is again carried through the tank of liquid, and this operation may be repeated many times depending upon the requirements.

The present method for carrying out this operation requires that the fabric be carried from the supply roll over a small roller and in frictional contact with a bar located adjacent to the small roller, and from there down into the liquid in the tank and up to another friction bar and small roller to the take off roller.

These friction bars being for the purpose of removing the excess liquid from the fabric and removing the wrinkles and serving as a guide to the travel of the fabric, but it has been found that the relation between the bar and the small roller must be adjusted or changed depending upon the material that is being treated, and also that the bars should be curved outwardly from the roller and that this curve should vary with different materials to be treated, all of which are not possible with the machines now in use for this purpose.

The object of the present invention is to provide a device for attachment to such tanks whereby the relative position of the friction bars with respect to the small guide rollers may be changed quickly and easily and without stopping the operation of the machine, so that the operator may make the proper adjustments to obtain the best results and for different materials.

Another object of the invention is to provide in a device of this kind means whereby the curvature of the friction or tension bars may be varied to accommodate the requirements for different fabrics and materials to insure the best results.

Another object of the invention is to provide means whereby as the fabric is transferred from the supply roller to the take off roller, the device will tilt within the tank and thus tend to keep the roller adjacent the take off roll approximately the same distance from this roll at all times and as the diameter of the roll increases.

Another object of the invention is to provide means whereby the rotation of either or both of the guide rollers may be prevented if desired so that the fabric is drawn with a sliding fric-

tional movement both over the tension bar and the adjacent guide roller.

Another object of the invention is to provide means whereby through the curvature of the tension bar the fabric will tend to be guided and kept to the center of the rollers in the same manner that a belt acts with respect to a crowned pulley.

With these and other objects in view, my invention consists in certain novel construction and combination of parts as will hereinafter be fully described and claimed and also illustrated in the accompanying drawings which form a part hereof and in which like figures of reference refer to corresponding parts in all of the views, and it is understood that slight changes may be made without departing from the spirit of the invention.

In the drawings:

Figure 1 is a side elevation of the device shown as attached to a tank (shown in section) and having supports and supply and take off rolls of fabric indicated by broken lines.

Figure 2 is a similar view of the same in a tilted position owing to the supply roll becoming smaller and the take off roll increasing in diameter.

Figure 3 is a top plan view of the same.

Figure 4 is a top plan view partly in section of the tension bars and their mounting and operating mechanism.

Figure 5 is an end view of the device as mounted in the tank, which is shown in section.

Figure 6 is a detail cross sectional view of one of the guide rollers and tension bar, showing their relation to each other.

Figure 7 is a detail view of one of the bearing members showing the means for locking the guide roller.

Figure 8 is a detail side view of the same.

Referring to the drawings:

The usual tank is indicated by the numeral 10 and is formed with the side edges 11, to which are secured the supports 12 for the shafts 13 and 14 which carry the supply roll of fabric 15 and the take off roll of fabric 16; these shafts being rotated in some suitable manner by the pulleys 17 and belts 18, or in any suitable manner so that their direction of rotation may be reversed at will by the operator.

My invention comprises a pair of bearings 19 attached to the tank edge 11 by the bolts 20 and formed with the aligned bearings within which are secured the stub shafts 21, upon which are mounted the members 22 by the caps and bolts 23

50

55

and 24 in such a manner that said members 22 can be rocked upon the shafts 21.

Said members 22 are formed with a longitudinal opening within which are secured the side supporting bars 25 which are here shown as rectangular in cross section, but which may be round or of any desired shape, material and size.

Upon said bars 25 and at each side of the member 22 and spaced therefrom are a pair of similar members 26 held in place by the screws 27, and formed with the depending arms 28 terminating in a head 29 to which is secured by the screw 30 a bearing member having a rotatable transverse shaft 31 upon which is mounted 15 the lower guide roller 32 which is submerged in the liquid within the tank.

Adjacent the outer ends of the bars 25 are mounted by the set screws in an adjustable manner the bearing members 33 which are formed on 20 their inner sides with bearings for the ends of the transverse guide roller shafts 34 which carry the guide rollers 35.

The lower part of said bearing members 33 are provided with the cap 36 secured by the screws 37 to form a guide way 38 within which is slidably mounted a bearing block 39 having a threaded bore for the adjusting screw 40 which is journaled in the ends 41 of the member 33 and provided at one end with the nut 42 and at 30 the other end with the hand wheel 43 for the purpose of moving or adjusting said bearing block 39 within said guide way; said bearing block 39 being locked in position by a bolt 44 threaded therein and clamping a washer 45 35 against the member 36.

The inner ends of the bearing blocks 39 extend from the inner sides of the members 33 and are provided with the sockets 46 for the turned ends of the tension bars 47 which are 40 mounted therein and which extend transversely across the tank in normal parallel relation to the guide rollers 35 and spaced therefrom, said spacing being regulated by the position of the bearing blocks 39.

45 For bowing or curving these tension bars 47 outward with respect to the guide rollers 35, I have provided the shoes 48 which are attached to said bars 47 by the screws 49 and which are formed with the studs 50 and to one of which is attached by the pin 51 the end of a tubular bar 52 formed with the internal threads 53; while to the other shoe 48 is attached by the pin 54 the socket 55 which is formed with a side slot 56 within which is placed an adjusting screw 57 which is threaded 50 into the inner end of a similar tubular bar 58 to the bar 52, in such a manner that by loosening said screw 57 said bar 58 will have a limited sliding movement within the socket 55; this bar 58 is also formed with the internal threads 59 but of an opposite lead to those in the bar 52; and within these bars 52 and 58 is threaded a double ended screw 60 having the right and left hand threads 61 and 62 and the hand wheel 63 secured thereon by the pin 9, and by the rotation 65 of the hand wheel 63 it will be seen that the tension bars 47 will be bowed outward or curved as shown in Figure 4.

For quick adjustment of the device, the locking screw 57 is loosened allowing the bar 58 to slide 70 within the socket 55 thus relieving the pressure exerted on the tension bars 47 and permitting

the hand wheel to be quickly rotated and the position of the bearing blocks 39 to be changed in the bearing members 33.

During the treatment of certain fabrics it may be desired to prevent the rotation of the guide rollers 35 so that the fabric is drawn over both the guide roller 35 and the tension bar 47 in frictional contact therewith, and to accomplish this, I have provided the members 33 with the two ears 64 between which is pivoted a latch 65 on the pin 66; said latch 65 being formed with a bent end 67 which when lowered will enter a slot 68 formed in the edge of the guide roller 35 and prevent the rotation of said roller, but which may be disengaged when desired.

Having thus described my invention, what I claim as new and desire to secure by Letters Patent, is:

1. In a tension device for textile machines and in combination with a tank, having alined bearings mounted thereon, of a frame mounted therein and capable of being rocked, a depending portion attached to said frame within said tank, a transverse roller carried thereby and having free rotary movement, bearing members mounted on 20 the outer ends of said frame and formed with bearings, transverse shafts mounted therein carrying guide rollers, bearing blocks adjustably mounted in said members and means for adjusting the same, transverse tension bars mounted 25 in said bearing blocks adjacent said guide rollers and means for bowing or curving said tension bars with relation to said guide rollers.

2. In a machine for immersing textile material in a liquid and comprising in part of a tank, of a 35 supporting frame pivotally mounted to said tank, a depending portion extending within said tank, a transverse roller carried thereby, transverse guide rollers adjustably mounted adjacent the ends of said supporting frame, tension bars 40 mounted adjacent thereto, means for adjusting said tension bars with relation to said guide rollers, and means for curving said tension bars outwardly from said guide rollers.

3. In a device of the class described, the combination with a tank having beam supports, of a frame pivotally mounted thereon and having a depending portion extending downwardly within said tank, a transverse roller mounted in said depending portion, bearing members adjustably 50 mounted on said frame adjacent the ends thereof, parallel rollers journaled in said members, tension bars mounted in said members below said rollers, means for adjusting the distance between said bars and said rollers, and means for curving 55 said tension bars.

4. In a machine for immersing textile material in a liquid and comprising in part of a tank, of a supporting frame pivotally mounted to said tank, a depending portion extending within said tank, a transverse roller carried thereby, transverse 60 guide rollers adjustably mounted adjacent the ends of said supporting frame, tension bars mounted adjacent thereto, means for adjusting said tension bars with relation to said guide rollers, means for curving said tension bars outwardly from said guide rollers, and means for temporarily preventing the rotation of said guide rollers.
